UNITED STATES PATENT OFFICE.

RAY H. MANSON, OF ELYRIA, OHIO, ASSIGNOR TO THE GARFORD MANUFACTURING COMPANY, OF ELYRIA, OHIO, A CORPORATION OF OHIO.

WARNING-SIGNAL.

1,318,572.

Specification of Letters Patent. Patented Oct. 14, 1919.

Application filed January 7, 1915. Serial No. 906.

To all whom it may concern:

Be it known that I, RAY H. MANSON, a citizen of the United States, and a resident of Elyria, in the county of Lorain and State 5 of Ohio, have invented certain new and useful Improvements in Warning-Signals; and I do hereby declare the following to be a full, clear, and exact description of the invention, such as will enable others skilled in 10 the art to which it appertains to make and use the same.

My invention relates generally to warning signals, such as find their principal use upon 15 automobiles, motor cycles, motor boats and the like, the invention in this application being more particularly classified among what are familiarly known as mechanical or hand-operated horns, wherein no electric current is used, but the power is applied directly by hand and transmitted through certain 20 mechanical devices to the sound producing member. The horn which I have invented is by no means the first of this type which has been invented or used, but those 25 hitherto in use, so far as I am aware, are open to many objections. They are expensive to make, not only from the multiplicity of their parts, but from the care and accuracy which is required in the manufacture of 30 these parts in order to secure the proper operation of the horn. For the reason that these parts must be accurate, the device becomes inefficient when the parts are even slightly worn, and especially so when the 35 parts become worn in any marked degree.

In certain of these horns the employment of numerous bearings requires considerable attention, in the nature of oiling, etc. In 40 certain forms it is necessary to apply considerable power to operate the horns, which inconveniences the driver, who generally operates the horn, while the blows rack the structure and injure the same. By my invention I produce a device which can be 45 cheaply made and most of whose parts can be conveniently manufactured by standard machinery and tools; in fact, most of the parts of my device are what are known as stampings, which, it is well known, are 50 cheaply and conveniently manufactured. The structure which I have invented requires no painstaking accuracy in the manufacture of the parts, or the application of any intricate processes, and when once assembled, will operate for great lengths of

time with little or no oiling. In addition to this, the structure thus produced is very durable, and even though certain of the parts become worn, it will continue to operate with accuracy and efficiency. I have eliminated 60 ratchets and pawls and gear wheels, and the trouble and care necessary to maintain the same. The horn is direct acting, and for this and other reasons, operates when struck lightly, eliminating the racking resulting 65 from hard blows applied in other forms of devices.

Another object of my invention is to provide yieldable connecting means between the parts, so that a severe blow will not injure 70 the operating parts.

Other objects of my invention and the invention itself will probably be better understood from a description of an embodiment thereof, such as is shown in the appended 75 drawing.

Figure 1 is an illustration of an embodiment of my invention shown partly in section, illustrating certain of the operating parts.

Fig. 2 is an elevation with the diaphragm and resonator removed, certain parts of the casing being cut away to illustrate better the mechanism.

Fig. 3 is a section through the rear casing, 85 showing a third view of the operating parts.

Fig. 4 is a view of a second embodiment of my invention with part of the casing cut away to show the mechanism.

Fig. 5 is a view of the mechanism and rear casing of the embodiment shown in Fig. 4, with the diaphragm and front casing removed.

Fig. 6 is a view showing in elevation the mechanism of the embodiment shown in Fig. 95 4 of the drawing, with the top of the casing cut away.

Fig. 7 is a detailed view of a portion of the apparatus employed in the embodiment shown in Fig. 4.

Referring now to the embodiment of my invention illustrated in Figs. 1 to 3 of the drawings, at 4 is shown a frame or casing which we will for convenience call the back casing to distinguish it from the front casing 5. In the form shown, the back casing 4 is turned up along its edge to form an annular flange 6 and a sound producing member, such as a vibratile diaphragm 7 is clamped 105 between the flange 6 and the front casing. 110

The front casing is provided with an opening 8 for the egress of sound waves and a flange 9 is turned up around said opening to which a resonator 10 may be connected. 5 These parts are all old and constitute no part of the invention of this application. Means are provided for actuating the diaphragm, which here consist of a roughened wheel 11 and an anvil 12 mounted in any 10 suitable manner upon the diaphragm. In the form shown a screw 13 is employed as the anvil and is connected to the diaphragm in any suitable manner, such as by nuts 15 and 16 on opposite sides of the diaphragm. 15 The wheel 11 is mounted upon a suitable axle, shown at 18, which is mounted on suitable bearings 19 and 20 supported in the frame or back casing 4. In the form illustrated, the axle 18 is counter-sunk at each 20 end, as shown at 21 and 22 and pointed pinions 23 and 24 employed which project into the holes counter-sunk into the end of the axle, forming a cheap and practically frictionless bearing for the wheel. 25 Means are provided for operating the wheel here shown as a plunger and associate parts. The plunger is illustrated at 30 and consists of a channel-shaped punching closed at one end, as shown at 31. The planes of 30 the side walls 31' of the channel are preferably parallel to the principal axis of the horn, and in the form illustrated, to the wheel 11. A handle or knob 32 is mounted on the top of the plunger, the handle being 35 bored out as shown at 33 and the open end of the plunger inserted therein and held there by any suitable means, such as by frictional engagement. The back casing 4 is perforated at 34 and 35 for the plunger, the edges 40 of the perforations being turned up to form flanges 36 and 37 which furnish suitable bearing surfaces for the plunger which reciprocates in these openings. The front of the top portion of the channel-shaped 45 punching is closed by a member 40, which may be a portion of the plunger, and which may be stamped out the same time the other portions of this plunger are stamped out. There is mounted upon the axle 18, preferably 50 in close proximity to the wheel 11, a toothed wheel 41, which is made of suitable size and dimension, and through which power may be applied to rotate the axle 18 and the wheel 11. The plunger is provided with a 55 flexible member, here shown as a chain 42 for rotating the axle and the wheel 11. This chain may be made in any suitable manner and in the form shown, consists of a flat link chain provided with catches 43 adapted 60 to engage the teeth on the wheel 41. The chain is connected at one end to a pin 44 passing through the side walls of the plunger. The chain passes upward, being concealed within and protected by the channel and 65 then around the axle and toothed wheel and

back again into the channel, its upper end being connected to one end of a spring 50. The other end of this spring is connected to a lug 56 on the end of the plunger and which in the form shown is integral with the member 40, the end of the member 40 being simply turned inward to form this lug. 70

A retrieving spring 60 is employed connected at one end to the plunger, in the form shown, by boring a hole 61 into the back of 75 the plunger, one end of the spring being formed into a hook 62 which is inserted into this opening. The other end of the spring is connected to the frame or to some other stationary part of the device. In the form 80 shown this is accomplished by employing a bracket 63 fastened to the rear wall of the back casing. Means are provided to limit the upward movement of the plunger, here shown as a catch 70 mounted in any suitable 85 manner upon the frame, such as by screws 71. In the form shown in Figs. 1 to 3 I employ a separating member 80 employed to separate the two parts of the coil of chain. This member is best illustrated in 90 Fig. 2 and its function will be readily understood from the drawing.

The operation of my device is as follows: The parts are normally in the position as illustrated in Fig. 1, and to operate the horn, 95 the driver applies pressure to the handle 32, depressing the plunger, the catches 43 engaging the teeth on the wheel and rotating the axle and wheel 11 as the chain passes over the toothed wheel in the descent of the 100 plunger. When the plunger has reached its way-down position, the power is withdrawn and the spring 60 returns the plunger to normal position, the chain passing idly over the wheel 41. During the descent of the 105 plunger the spring 50 keeps the chain taut, insuring the desired engagements between the catches 43 and the ratchet wheel. However, owing to the flexibility of the spring, the chain on the return movement will be 110 allowed to slack slightly to prevent the toothed wheel from being caught in passing over any uneven portions of the chain. Furthermore, this spring will take up any 115 expansion or contraction of the chain, due to such conditions of wear of the parts, always insuring a close gripping action between the chain and the ratchet wheel.

It will be seen that the parts are few and simple and inclosed and protected, no ratchets or spur wheels being employed and no rack exposed, as is common in many hand horns. It will also be seen that the parts require little or no oiling or other attention, and that I produce one of those structures in 125 which unequal wear and tear falls upon a single member which eventually will give way first, but will render the other elements useless or inoperative until the injured or destroyed member is replaced. 130

In the embodiment illustrated in Figs. 4 to 7 inclusive, the plunger is inclined, thereby changing the manner in which the force is applied to the mechanism and increasing 5 the length of stroke for the size of casing employed. Horns of this type are frequently mounted on an automobile or other conveyance in advance of the driver and somewhat below the natural position of his 10 hand, so that his natural stroke would be inclined toward the long axis of the horn. By inclining the plunger I make it more convenient for him to operate the device. As stated, this also enables me to increase 15 the length of stroke for the size of horn employed, with the result that the apparatus may be more compact and the roughened wheel given sufficient rotation to produce a signal without utilizing any fly-wheel effect 20 of the roughened wheel, which creates a disagreeable note on the end of the signal.

In the form illustrated in Figs. 4 to 7 inclusive, the rear casing is shown at 100, the diaphragm at 101, the front casing at 102, the resonator at 103; the roughened wheel is shown at 104, the axle at 105 and the bearings therefor, at 106 and 107. The toothed wheel is shown at 108 and the hollow plunger at 109. In this form a guide 25 is provided for the plunger, shown at 150. This guide is also channel-shaped and the plunger fits within the same, sliding back and forth therein during its operation.

The flexible chain is shown at 110. In 30 this embodiment the chain is connected at one end through suitable means, such as a pin 111, to the plunger, passed over the axle and over a pulley 112 mounted in the end 113 of the member 150. The other end of 35 the chain is connected to a link 115 connected to one end of a coil spring 116, the other end of the coil spring being connected to the plunger, as illustrated at 117. In this form, as will be seen, the links of the chain 40 throughout are parallel to each other and pass over the axle in a plane substantially perpendicular to the long axis thereof. The link 115 is preferably mounted inside of 45 the hollow plunger and is provided at one end with ears 120 through which a pin 121 passes to connect the end of the chain 110 to the link 115. The other end of the link 50 is provided with a catch 122 for the end of the spring 116. A retrieving spring 130 is 55 employed connected at one end to the frame through any suitable means, such as a lug 131, here shown as a portion of the member 150, and at the other end to the plunger through any suitable means, such as a pin 60 132 connected to the plunger. The pulley 112 is mounted upon an axle 160 mounted in ears 161 formed on the end of the member 150.

In the operation of the embodiment illustrated in Figs. 4 to 7 inclusive power is ap-

plied to the handle 170 and the plunger depressed, the same riding down the channel in the member 150 and drawing the chain over the ratchet wheel, the catches 171 on the chain engaging the ratchets and rotating the 70 axle and the roughened wheel, the spring 116 keeping the chain taut and in close engagement with the pulley and toothed wheel, whereby it is assured that the catches on the chain will engage the teeth on the wheel. 75 The spring 130 will be extended. At the end of the stroke the handle is released and the spring 130 retrieves the parts, the chain now passing idly over the toothed wheel until the parts are restored to normal. The spring 80 116 will in this embodiment of my invention also take up any unevenness or change in the shape of parts due to the wearing thereof or other causes.

I have illustrated these modifications and 85 these details simply for the purpose of better describing my invention and not that I wish to be limited to such forms and details; in fact, it will be apparent to those skilled in the art that numerous and extensive departures may be made from the forms and details here illustrated without departing from the spirit of the invention.

I claim:

1. In an automobile horn, the combination 95 of a vibratile, sound producing diaphragm, means including a roughened wheel for operating said diaphragm, an axle on which the wheel is mounted and means for rotating the wheel including a plunger, a 100 flexible member carried by the plunger and a device on the axle of the roughened wheel engaged by the flexible member during the operation of the plunger.

2. In an automobile horn, the combination 105 of a vibratile, sound producing diaphragm, means for actuating the diaphragm including a roughened wheel, an axle on which the wheel is mounted, a plunger, a 110 looped, flexible member carried by the plunger encompassing the axle within the loop and means on the axle to engage the flexible member, whereby the axle is rotated when the plunger is depressed.

3. In an automobile horn, the combination 115 of a vibratile, sound producing diaphragm, means to operate the diaphragm including a roughened wheel, an axle upon which said wheel rotates, a plunger, a chain carried by 120 said plunger having a loop encompassing the axle, catches on said plunger and corresponding catches on the axle, whereby the chain and plunger operate the wheel when actuated.

4. In an automobile horn, the combination 125 of a vibratile diaphragm, means for operating the same including a roughened wheel, a depressible plunger, a flexible member carried by the plunger, power transmitting means between the flexible member and the 130

roughened wheel, whereby the roughened wheel is operated when the plunger is depressed.

5. In an automobile horn, the combination of a vibratile diaphragm, means for operating said diaphragm including a roughened wheel, means for operating the wheel including a plunger and a flexible member carried thereby and power transmitting 10 means between the flexible member and the roughened wheel.

6. In an automobile horn, the combination of a vibratile, sound producing diaphragm, means for vibrating the same, including an 15 anvil on the diaphragm and a roughened wheel adapted to engage the anvil, an axle on which the wheel is mounted, a frame, bearings in the frame for the axle, a toothed wheel on the axle, a hollow, compressible 20 plunger, bearings in the frame for the plunger, a chain in the hollow plunger having a loop encircling the axle, catches on the chain for engaging the teeth on the wheel, one end of the chain being connected directly 25 to the plunger, a spring connecting the other end of the chain to the plunger and a second spring for returning the plunger to normal when it has been depressed and released.

7. In an automobile horn, the combination 30 of a frame, a vibratile diaphragm mounted in the frame, means for operating the diaphragm including a roughened wheel, a compressible plunger mounted in the frame and inclined at an angle to the diaphragm and means for communicating power from the plunger to the roughened wheel, including a chain connected to the plunger and moved thereby, and means to transmit motion from the chain to the roughened wheel.

40 8. In an automobile horn, the combination of a vibratile diaphragm, a frame in which the diaphragm is mounted, means to operate the diaphragm including a roughened wheel, an inclined channel in the frame inclined to the diaphragm, a plunger mounted in the channel and reciprocating therein, a chain connected to the plunger and moving when said plunger is moved and means to communicate motion from the chain to the roughened wheel, whereby the wheel is operated when the plunger is operated.

9. In an automobile horn, the combination 55 of a vibratile diaphragm, a frame in which said diaphragm is mounted to vibrate, an anvil on said diaphragm, a rotatable roughened wheel adapted to engage the anvil and operate the diaphragm, an axle, bearings for said axle in said frame, said wheel being tightly fastened to said axle, a toothed wheel on said axle adjacent to said roughened wheel, a plunger adapted to be operated by hand, bearings in the frame for said plunger, said plunger being provided with a channel, a flexible chain connected 60 at one end in the channel of the plunger, a

spring connected at one end to the other end of said chain, means to connect the other end of the spring to the plunger, said chain being provided with a loop encircling the toothed wheel on said axle, all of the chain except the loop being normally positioned in the channel in the plunger, and means on the chain to engage the teeth on the toothed wheel.

10. In an automobile horn, the combination 75 of a vibratile diaphragm, an anvil on said diaphragm, a frame, bearings in said frame, an axle in said bearings, a roughened wheel on said axle adapted when operated to vibrate the diaphragm through the 80 anvil, a toothed wheel on said axle, a plunger inclined with respect to said diaphragm, bearings in the frame for the plunger, a guide for said plunger in said frame, said plunger being provided with a channel, a 85 pulley in said frame, a flexible chain connected at one end to said plunger and extending over said toothed wheel on the axle and said pulley, a link in the channel in the plunger connected to the other end of the 90 chain, a spring connected to the other end of the link and to the plunger, and means to restore said plunger to normal when depressed and released.

11. In an automobile horn, the combination 95 of a frame, a diaphragm in the frame, an anvil on the diaphragm, a roughened wheel rotatably supported in the frame adapted when rotated to operate the diaphragm through the anvil, a plunger supported to reciprocate in the frame, means including a flexible member through which the plunger operates the roughened wheel and yielding connecting means between the plunger and the flexible member.

105 12. In an automobile horn, the combination of a frame, a vibratile diaphragm, means for operating said diaphragm including a roughened wheel, apparatus for operating said wheel including a plunger inclined to said diaphragm, bearings for the guide in diagonally opposite parts of the frame, a hollow guide for said plunger mounted in the frame and mechanism for communicating power from the plunger to 110 the roughened wheel.

13. In an automobile horn, the combination 115 of a frame, a vibratile diaphragm, means for operating said diaphragm including a roughened, movable member, apparatus for operating said member including a plunger inclined to the diaphragm, a guide for said plunger extending between diagonally opposite corners of the frame, and mechanism for communicating power from the plunger 120 to the roughened member.

14. In an automobile horn, the combination 125 of a frame, a vibratile diaphragm mounted in the frame, means for operating said diaphragm including a rotary, rough-

ened wheel and an anvil on the diaphragm, apparatus for operating said wheel including a manually operable plunger inclined at an angle to the diaphragm, a channel in the frame for the plunger inclined to the plane of the diaphragm in which the plunger reciprocates when operated, bearings for the channel, one in the upper rear part of the frame and the other in the lower front part 5 thereof, an axle in the frame upon which said wheel is mounted and mechanism for

communicating power from the plunger to the roughened wheel, whereby the wheel is rotated when the plunger is reciprocated.

In witness whereof I have signed my 15 name, in the presence of two witnesses, this 22nd day of Dec., 1914.

RAY H. MANSON.
